US00D796961S

(12) **United States Design Patent** (10) Patent No.: **US D796,961 S**
Klein et al. (45) Date of Patent: **** Sep. 12, 2017**

(54) **BOTTLE WITH CAP**

(71) Applicant: **LIFE TECHNOLOGIES CORPORATION**, Carlsbad, CA (US)

(72) Inventors: **Sandro Klein**, Irvine, CA (US); **Xin Mathers**, Poway, CA (US); **Pawel Zygier**, Warsaw (PL); **Adrian Bird**, Bicester (GB)

(73) Assignee: **Life Technologies Corporation**, Carlsbad, CA (US)

(**) Term: **15 Years**

(21) Appl. No.: **35/001,139**

(22) Filed: **Jan. 11, 2016**

(80) **Hague Agreement Data**

Int. Filing Date: **Jan. 11, 2016**

Int. Reg. No.: **DM/091642**

Int. Reg. Date: **Jan. 11, 2016**

Int. Reg. Pub. Date: **Jul. 29, 2016**

(51) **LOC (10) Cl.** 09-01

(52) **U.S. Cl.**

USPC **D9/522**

(57) **CLAIM**

The ornamental design for a bottle with cap, as shown and described.

DESCRIPTION

1. Bottle with cap

1.1 : Perspective front

1.2 : Perspective back

1.3 : Front

1.4 : Back

1.5 : Left

1.6 : Right

1.7 : Top

1.8 : Bottom

1.9 : Perspective front

1.10 : Perspective back

1.11 : Front

1.12 : Back

1.13 : Left

1.14 : Right

1.15 : Top

1.16 : Back

1.17 : Perspective front

1.18 : Perspective back

1.19 : Front

1.20 : Back

1.21 : Left

1.22 : Right

1.23 : Top

(Continued)

1.24 : Bottom
1.1-1.8: Bottle with cap; **1.9-1.16**: Bottle; **1.17-1.24**: Cap.

1 Claim, 24 Drawing Sheets
